UNITED STATES PATENT OFFICE

172,716

MOLDING STRIP

Robert B. Jones, Dearborn, Mich., assignor to
Packard Motor Car Company, Detroit, Mich.,
a corporation of Michigan

Application October 14, 1953, Serial No. 27,178

Term of patent 14 years

(Cl. D14—6)

To all whom it may concern:

Be it known that I, Robert B. Jones, have invented a new, original, and ornamental Design for a Molding Strip, of which the following is a specification, reference being had to the accompanying drawings, forming a part hereof, and in which:

Fig. 1 is a side elevational view of a molding strip, showing my new design.

Figs. 2 and 3 are sectional showings taken along the respective lines 2—2, 3—3 of Fig. 1.

Fig. 4 is an enlarged fragmentary view based on Fig. 1; and

Figs. 5, 6 and 7 are sections taken along the respective lines 5—5, 6—6 and 7—7 of Fig. 4.

The dotted line disclosure of the automobile in Figure 1 and of the insert medallion in Figures 1, 4 and 6 is shown only for the purpose of illustration.

I claim:

The ornamental design for a molding strip, as shown and described.
